UNITED STATES PATENT OFFICE.

ALBERT E. JOHNSON AND MERTON E. JOHNSON, OF BEVERLY, MASSACHUSETTS, AS-SIGNORS TO UNITED SHOE MACHINERY CORPORATION, OF PATERSON, NEW JERSEY, A CORPORATION OF NEW JERSEY.

WETTING MACHINE.

Application filed November 21, 1919. Serial No. 339,711.

To all whom it may concern:

Be it known that we, ALBERT E. JOHNSON and MERTON E. JOHNSON, citizens of the United States, residing at Beverly, in the county of Essex and State of Massachusetts, have invented certain Improvements in Wetting Machines, of which the following description, in connection with the accompanying drawings is a specification, like referring 10ence characters on the drawings indicating like parts in the several figures.

Our invention relates to machines for wetting various articles, for example shoe parts, as innersoles. With such work, the surface 15 to be wet is often of a non-absorptive character, a condition which may be produced in leather by the tannage. Objects of the invention are to overcome this difficulty, and to provide a machine which will effectively 20 wet resistive material, and which may generally be operated to moisten work thoroughly and rapidly.

In the attainment of these objects, a feature of the invention consists in a novel organization for causing the fluid to be applied to enter the work, as by a relative travel of co-operating members to bring the work under the influence of fluid-applying means. In the illustrated machine, an absorbent material is supplied with fluid from a receptacle in which it is supported, and the work is drawn over the absorbent material and the contained fluid rubbed into it by the travel of a conveyor. Preferably, 25 the absorbent material or other fluid-applying means has its applying surface formed in sections, and a work-conveyor operates between and in proximity to the sections, there being shown means, as 30 a tension device, for maintaining the conveyor in proximity to the absorbent material, or in the space between the sections. In its travel, the work is held against the applying member, in the present instance by 35 a series of members extending in the direction in which the work proceeds, this holding means being yieldable. By this arrangement, the work is not only kept in rubbing engagement with the applying member, 40 but is also held firmly against the conveyor.

In operating the work-conveyor in a fluid receptacle at a considerable speed, as is possible with the present machine, there is a tendency to carry the fluid over the end of

the receptacle with the work at the point 55 where the latter emerges. To prevent this, as a feature of the invention, we provide novel means for raising the work as it leaves the receptacle. This may be accomplished by altering the direction of movement of the 60 conveying means, its angular relation to the applying means being changed beyond the holding means. By this expedient, a considerable portion of the adhering fluid which has not been absorbed by the work is permitted to drain back to the receptacle before 65 said work leaves it.

A particular embodiment of the invention is illustrated in the accompanying drawings, in which—

Fig. 1 is a top plan view, with parts broken away, of our improved wetting machine;

Fig. 2 is a side elevation thereof; and

Fig. 3 is an enlarged end elevation looking from the right in Fig. 2.

Shown as mounted upon a base or standard 10 is a receptacle 12, preferably shallow and elongated in one direction. Rising above the receptacle at one side of and supported upon the base is a tank 14, at the top of which is shown a filling opening provided with an air-tight closure 16. From the bottom of the tank leads a discharge pipe 18, the flow through which may be controlled by a cock 20. The pipe 18 communicates with the interior of the receptacle 12, it being here illustrated as extending into the open upper end of an elbow 22, which is connected with an opening in the side wall of the receptacle. This arrangement furnishes a barometric feed, which maintains in the receptacle a fluid level corresponding to the discharge opening at the bottom of the pipe 18. To cause the fluid to pass from the tank to the receptacle steadily rather than in irregular gushes, we prefer to form at one side of the bottom wall of the pipe a notch 24, through which the fluid flow is steadily maintained as the work is moistened in and thus withdraws fluid from the receptacle. There may be a drain opening at the bottom of the receptacle normally closed by a plug 25.

Projecting upwardly from the bottom of the receptacle are pairs of lugs 26, 26 and 28, 28 situated near its opposite ends. Carried upon horizontal upper surfaces of the lugs is a supporting member, preferably in

the form of a grating and being in two sections 30, 30 separated by a space 32 which lies longitudinally of the receptacle at or near its center. Each of the lugs 28 has at 5 its outer side an upstanding shoulder 34, and against these shoulders the grating sections may be forced by screws 36 threaded through the opposite receptacle wall. Drawn across the tops of the grating sections by pairs of bars 38, 38 secured to the 10 ends of the sections by screws 40, are covering sheets 42 of absorbent material, as burlap. The location of the sheets with relation to the discharge opening of the pipe 18 is such that they are maintained substantially 15 at the level of the fluid and constantly and uniformly moistened.

Arranged to travel across the end walls of the receptacle, through the space 32 between the grating sections and then below the receptacle, is an endless conveyor, conveniently furnished by a chain 44. This chain is supported upon rolls 46 and 48, the former roll being rotatably mounted upon a 25 bracket 50 fixed at one end of the receptacle, while the roll 48 is journaled upon a bracket or slide 52 mounted to move in ways formed at the bottom of the receptacle. A spring 54, extending between a pin 56 depending 30 from the under side of the receptacle and a pin 58 secured in the slide, exerts its tension to separate the roll 48 from the roll 46, and thus hold the chain taut with its upper run 35 substantially in transverse alinement with the absorbent material. The chain may be driven by a pulley 60 fast upon the spindle of the roll 46, over which pulley and over guide pulleys 64 a belt 62 leads to some suitable 40 source of power. In the periphery of the driven roll 46 are secured radial pins 66 arranged to enter openings 68 in alternate links of the chain 44, these serving to furnish positive engagement between the chain 45 and its driving means. Outwardly from the intermediate links of the chain extend pointed projections 70 for the purpose of engaging the work to carry it over the absorbent material. The ends of the conveyor, 50 where it is exposed to accidental contact with the person of the operator or objects about the machine, is protected by guards 72, 72.

Lying across the top of the receptacle 55 near each end is a supporting bar 74 movable vertically upon studs 76 rising from openings in lugs formed upon the side walls of the receptacle and secured therein by set screws 78. In each support is a series of 60 vertical openings, in which are fixed by set screws 80 the upturned ends of contact rods 82, the main portions of which extend horizontally above and in close proximity to the upper surface of the absorbent material 65 upon both grating sections. Springs 84

surround the studs 76, contacting at their lower ends with the supporting bars, and co-operating at their upper extremities with nuts and lock nuts 86. As thus organized, the rods 82 yieldingly hold the work against 70 the absorbent material and also against the projections 70 of the conveyor to cause its effective engagement and its advance thereby in firm rubbing contact with the former. For convenient presentation of the work to 75 the conveyor, we furnish at the end of the receptacle, above the roll 48, a table 88, at the center of which is a slot 90 to permit the passage of the conveyor. Guides 92, 92, converging inwardly at opposite sides of 80 the table, form a throat for directing the work into the machine. Fixed to the side of the adjacent supporting bar 74 is a curved pressure plate 94 preferably formed of spring metal, with its under surface reaching over the table close to the points of 85 the conveyor projections 70. As the work is inserted between this plate and the table, the former insures the feeding engagement 90 of the projections with the work. The diameter of the roll 48 is such that the conveyor at this end enters the receptacle in a substantially horizontal direction at the level of the absorbent material. The roll 46 is of greater diameter, so that its top lies 95 at some distance above the end wall of the receptacle. The central pair of rods 82 are situated opposite the space 32, so that they may contact with the edges of the conveyor chain, or with the work carried thereby. After the chain, in its travel from right to 100 left, as viewed in Fig. 2 of the drawings, passes beyond the curved end portions of the rods 82, it is directed by the roll 46 upwardly, emerging from the receptacle at a 105 substantial angle with relation to the surface of the absorbent material. In consequence of this, the unabsorbed fluid adhering to the work has an opportunity to drain back to the receptacle before the work passes over the end wall. It is at this point delivered upon a slotted plate 96, and, as the conveyor changes its direction, moving 110 downwardly about the outer side of the roll 46, the conveyor projections are withdrawn 115 from the work, and it is thrown from the plate into a suitable receptacle.

It is thought that the operation of the machine will be clear from what has already 120 been said; but to outline it briefly, it may be stated that the work pieces, as innersoles which are to be wet upon one side, are fed one by one upon the table 88, being centralized by the guide walls 92 and urged into engagement with the conveyor projections 125 by the plate 94. These projections thereupon carry the work pieces between the moistened absorbent material 42 and the contact rods 82, the latter maintaining the feeding engagement, and at the same time so 130

causing the rubbing of the surface to be wet in its travel over the material 42 that its fibers are disturbed, facilitating the absorption of the fluid, which is thoroughly worked in to the surface. After passing beyond the contact rods, the direction of travel of the work is changed upwardly to carry it clear of the end wall and allow the excess of fluid to drain back to the receptacle before its final delivery. By an adjustment of the position of the upturned ends of the rods 82 in the supporting bars, the machine may be arranged to operate effectively upon stock of different thicknesses, and by altering the tension of the springs 84 by positioning the nuts 86, the force of the rubbing action may be changed to adapt the machine to the requirements of stock of different character.

Having described our invention, what we claim as new and desire to secure by Letters Patent of the United States is:

1. A wetting machine comprising co-operating extended members arranged for simultaneous contact with a plurality of work-pieces, applying means associated therewith for subjecting the work to the action of a fluid, and means arranged to produce relative travel of the members and thereby bring the work into contact with the fluid-applying means.

2. A wetting machine comprising co-operating extended members, absorbent material associated with one of said members, and means arranged to produce movement of the other member and thereby move the work along the absorbent material.

3. A wetting machine comprising a stationary support, a covering for the support, means for supplying a fluid to the covering, and a conveyor arranged to move simultaneously a plurality of work-pieces in contact with the support-covering.

4. A wetting machine comprising a stationary member presenting an extended supporting surface, means resting upon said surface and arranged to apply a fluid to the work, and a conveyor arranged to travel along the support and to engage the work.

5. A wetting machine comprising a fluid receptacle, absorbent material supported therein, and a work-conveyor arranged to travel along the absorbent material.

6. A wetting machine comprising a receptacle, means for maintaining a fluid at a constant level therein, a sheet of absorbent material supported at the fluid level, and means arranged to draw work in contact with the absorbent material.

7. In a wetting machine, a fluid receptacle, a fluid-applying member situated in the receptacle and presenting a sectional applying surface, and a work-conveyor operating between the sections and in proximity to the plane of the applying surface.

8. In a wetting machine, a fluid receptacle, a fluid-applying member situated in the receptacle and presenting a sectional applying surface, and a conveyor operating between the sections and having work-engaging projections extending out of the plane of the applying surface.

9. A wetting machine comprising co-operating extended members, absorbent material associated with one of said members, means arranged to produce movement of the other member and thereby move the work along the absorbent material, and means to maintain the movable member in proximity to the absorbent material.

10. A wetting machine comprising a stationary support, means associated therewith for applying a fluid to the work, a conveyor arranged to move the work in contact with the fluid-applying means, and a tension device to maintain the conveyor in proximity to the fluid-applying means.

11. In a wetting machine, a fluid receptacle, a sectional fluid-applying member in the receptacle, a work-conveyor operating between the sections of the applying member, and a tension device drawing the conveyor into the space between the sections.

12. In a wetting machine, an extended fluid-applying member, means traveling along the applying member to move the work thereover, and means for holding the work against the applying member.

13. In a wetting machine, an extended fluid-applying member, means traveling along the applying member to move the work thereover, and means extending along the surface of the applying member for holding the work against the applying member.

14. In a wetting machine, an extended fluid-applying member, means traveling along the applying member to move the work thereover, and yieldable means for holding the work against the applying member.

15. In a wetting machine, an extended fluid-applying member, means traveling along the applying member to move the work thereover, and a series of members for contact with the work extending in the direction of travel.

16. In a wetting machine, an extended fluid-applying member, means traveling along the applying member to move the work thereover, a series of members for contact with the work extending in the direction of travel, and springs arranged to press the members toward the applying member.

17. In a wetting machine, an extended fluid-applying member, means traveling along the applying member to move the work thereover, a series of members for contact with the work extending in the direction of travel, springs arranged to press the mem-

- bers toward the applying member, and means arranged to vary the tension of the springs.
18. In a wetting machine, an extended fluid-applying member, means traveling along the applying member to move the work thereover, a series of members for contact with the work extending in the direction of travel, and a movable support for the members at each end of the series.
19. In a wetting machine, an extended fluid-applying member, means traveling along the applying member to move the work thereover, a series of members for contact with the work extending in the direction of travel, a movable support for the members at each end of the series, and springs cooperating with the supports.
20. In a wetting machine, a member presenting a fluid-applying surface, a work-conveyor traveling along the applying surface, and a work-pressing member co-operating with the conveyor.
21. In a wetting machine, a fluid-applying member, a work-conveyor traveling along the applying member, a work-pressing member, and a tension device arranged to draw the conveyor against the pressing member.
22. In a wetting machine, a fluid receptacle, a fluid-applying member situated in the receptacle, means extending along the applying member and arranged to hold the work in contact therewith, and a conveyor arranged to move the work between the applying means and holding means.
23. In a wetting machine, a receptacle, means for maintaining fluid at a constant level therein, a grating situated near the fluid level, absorbent material carried by the grating, and an endless conveyor arranged to move the work in contact with the absorbent material.
24. In a wetting machine, a receptacle, means for maintaining fluid at a constant level therein, a grating situated near the fluid level, absorbent material carried by the grating, and an endless conveyor having projections arranged to move the work in contact with the absorbent material.
25. In a wetting machine, a receptacle, means for maintaining fluid at a constant level therein, a grating situated near the fluid level, absorbent material carried by the grating, an endless conveyor arranged to move the work in contact with the absorbent material, supports for the conveyor one of which is mounted for movement, and means for moving the support to apply tension to the conveyor.
26. In a wetting machine, a receptacle, means for maintaining fluid at a constant level therein, separated sections of grating situated near the fluid level, absorbent material carried by the grating sections, and an endless conveyor movable between the sections.
27. In a wetting machine, a receptacle, means for maintaining fluid near a constant level therein, separated sections of grating situated at the fluid level, absorbent material carried by the grating sections, an endless conveyor movable between the sections, and a spring drawing the conveyor into alignment with the grating.
28. In a wetting machine, a receptacle, means for maintaining fluid at a constant level therein, a grating situated near the fluid level, absorbent material carried by the grating, an endless conveyor arranged to move the work in contact with the absorbent material, and separated contact members extending over the absorbent material in the direction of movement of the conveyor.
29. In a wetting machine, a receptacle, means for maintaining fluid at a constant level therein, a grating situated near the fluid level, absorbent material carried by the grating, an endless conveyor arranged to move the work in contact with the absorbent material, supports extending across the absorbent material transversely to the direction of movement of the conveyor, and members for contact with the work mounted upon the supports.
30. In a wetting machine, a receptacle, means for maintaining fluid at a constant level therein, a grating situated near the fluid level, absorbent material carried by the grating, an endless conveyor arranged to move the work in contact with the absorbent material, supports extending across the absorbent material transversely to the direction of movement of the conveyor, members for contact with the work mounted upon the supports, and means co-operating with the supports to force the contact members toward the absorbent material.
31. In a wetting machine, a fluid receptacle, means provided with spaced projections for separately engaging and moving successive work-pieces into and out of the receptacle, and means arranged to raise each piece as it leaves the receptacle.
32. In a wetting machine, a fluid receptacle, a fluid-applying member therein, a co-operating work-conveyor movable within and out of the receptacle, and means arranged to change the direction of movement of the conveyor near its point of emergence from the receptacle.
33. In a wetting machine, a fluid receptacle, and means for moving work along the level of the fluid and out of the receptacle, said moving means being situated above and substantially parallel to the fluid-level in the receptacle and upwardly inclined at the end of said receptacle.
34. In a wetting machine, an extended fluid-applying member, means traveling

along the applying member to move the work in contact with the absorbent material, and movable supports for the conveyor one of which supports is outside the receptacle and extends above the absorbent material.

5 and means arranged to change the angular relation of the traveling means to the applying means beyond the holding means.

35. In a wetting machine, a fluid receptacle, a fluid-applying member situated in the 10 receptacle, means extending along the applying member and arranged to hold the work in contact therewith, and a conveyor arranged to move the work between the applying means and holding means, said conveyor 15 extending beyond the holding means and rising above the applying means.

36. In a wetting machine, a receptacle, means for maintaining fluid at a constant level therein, a grating situated near the 20 fluid level, absorbent material carried by the grating, an endless conveyor arranged to

37. In a wetting machine, a receptacle, means for maintaining fluid at a constant level therein, a grating situated near the fluid level, absorbent material carried by the 30 grating, an endless conveyor arranged to move the work in contact with the absorbent material, movable supports for the conveyor one of which supports is outside the receptacle and extends above the absorbent material, and means for holding the conveyor within the receptacle near the level of the 35 absorbent material.

In testimony whereof we have signed our names to this specification.

ALBERT E. JOHNSON.
MERTON E. JOHNSON.
